UNITED STATES PATENT OFFICE

2,303,156

LAMP SOCKET

Frank D. Bryant, Stratford, and William R. Young, Fairfield, Conn., assignors to General Electric Company, a corporation of New York

Application April 23, 1941, Serial No. 389,870

3 Claims. (Cl. 173—328)

Our invention relates to a lamp socket and more particularly to a lamp socket for tubular electric lamps, for example, fluorescent lamps of the type now in commercial use.

One object of our invention is the provision of an improved form of lamp socket of the type described so constructed and arranged as to lock the lamp in position.

Another object of our invention is to provide a lamp socket with locking means operable without the necessity of rotating the lamp.

In the accompanying drawing, Fig. 1 is a view of a socket constructed in accordance with our invention with the front cover removed showing the contact pins of a lamp in seated position but prior to locking; Fig. 2 is a view similar to Fig. 1 showing the lamp pins in locked position; Fig. 3 is a sectional view through the socket taken along the line 3—3 of Fig. 2; Fig. 4 is another sectional view through the socket taken along the line 4—4 of Fig. 1; and Fig. 5 is an exploded view of the socket.

Referring to the drawing, we have shown a socket 10 designed for use with double-ended discharge lamps of the type now in commercial use, for example, fluorescent lamps. Such lamps are provided with an elongated glass envelope closed at each end by ferrules carrying spaced contact pins for connection to the cathodes at each end of the lamp. Since fluorescent lamps of this type are well known, such a lamp is not shown by the drawing with the exception that the lamp contact pins, which cooperate with the socket, are shown in dotted lines in the figures and are designated 11.

The socket 10 comprises a housing 12 of insulating material, such as a molded plastic, provided in one face with recesses 13 and 14 separated by a wall 15. An opening 16 of annular form is likewise formed in the face but spaced from the recesses; the opening extends to the upper edge of the housing, as shown at 17. The housing thus described may be molded in a single piece, as shown by Fig. 5. The recess and opening may be covered with a closure plate 18 of insulating material, such as sheet fiber, which rests flush with a flanged wall 19 on the periphery of the housing and is secured in position by a screw 18'.

The socket is provided with fixed contact members 20 and 21 located in the recesses 13 and 14, respectively. At one end each contact member is provided with a curved contact surface 22 which extends through an opening 23 into the opening 16. At the other end, each

5 contact member is formed with a laterally extending terminal portion 25 seated in a groove 26 formed in the base of the housing. Each terminal portion carries a binding screw 27 for connection to an electrical circuit, access to the binding screws being attained through openings 28 formed in the base of the housing. The contact members 20 and 21 are made of flexible material, such as spring bronze and are biased so that the contact surfaces 22 tend to extend through the openings in the wall 24, as shown by Fig. 5.

20 Cooperating with the fixed contact members 20 and 21 are movable contact elements 29 and 30 carried by a rotatable element or disk 31 (Fig. 5) of annular form which is located within the annular opening 16. The disk 31 is made in two parts 32 and 33 of insulating material, such as a molded plastic. Each part is formed with diametrically opposite recesses 34 for receiving the contact elements 29 and 30. The recesses 34 are provided with slots 35 at one end for receiving the bent-over tangs 36, formed on the ends of the contact elements so that the elements are held in fixed position on the disk. In assembling the contact elements on the rotatable disk, the contacts are first placed in the recesses on one part of the disk with the tangs 36 resting in the slots 35 and thereafter the other part is moved to fit the contact elements in the corresponding slots; the parts 32, 33 are then secured together by any suitable fastening means, such as screws 37 extending through aligned openings 38 in the parts 32, 33 of the disk 31. In assembled position, the contact elements 29 and 30 lie flush with the outer periphery of the disk 31 and the contacts are slightly curved to conform to the contour of the disk. This means that when the disk is assembled in the opening 16, the contact elements are freely rotatable within the housing along with the disk. The contact elements 29 and 30 are located on the disk to cooperate with the flexible contact blades 20 and 21, respectively. Normally the contact surfaces 22 of the contact blades 20 and 21 ride over the outer surfaces of the rotatable contact elements. In locked position, however, the contact surfaces 22 snap into depressions 39 formed in the contact blades 29 and 30. This aids in preventing accidental rotation of the disk. The disk may be rotated manually in any suitable manner as by a handle 40.

45 For receiving the lamp contact pins the rotatable disk is provided with a diametrical slot 41 of a width and depth to permit seating of the lamp

pins in the manner shown by Fig. 1. A slot 41' is formed in the cover 18 in alignment with the slot 41. At opposite ends the slot 41 is formed with curved extensions 42 extending in opposite directions so that the diametrical slot and extensions form a slot in the general shape of the letter Z. The extensions 42 merge with the recesses 34 so that portions of the movable contact elements 28 and 30 extend into the extensions; these portions are formed with depressed contact surfaces 43 for engaging the lamp pins in a manner now to be described.

In mounting the lamp on the socket, the spaced contact pins 11 of the lamp are inserted laterally in alignment into the slot 41 to the position shown by Fig. 1. Thereafter the rotatable disk 31 is moved clockwise to the position shown by Fig. 2. This moves the arcuate extensions 42 around the contact pins and brings the contact surfaces 43 of the movable contact elements 28 and 30 into engagement with the lamp pins completing a circuit to the lamp. At this point the flexible fixed contact blades 20 and 21 snap into the depressions 38 preventing the rotatable disk from becoming dislodged or jarred out of position. Rotation of the disk is limited by engagement of the handle 40 with the sides of the opening 17. The lamp is securely locked in position on the socket by the rotatable disk since in circuit closing position the open end of the slot 41 is rotated to a position where it is closed by the wall 24 of the housing. Accidental rotation of the lamp is prevented by the fixed slot 41' in the cover 18 through which the contact pins are moved at the same time that they enter the slot 41.

Our socket provides a construction which locks the lamp in position and simultaneously completes a circuit to the lamp. The construction is particularly useful in those cases wherein it is difficult to rotate the lamp yet where it is desired to lock it in position. This is of advantage in cases where the associated reflector or fixture closely surrounds the lamp, making movement of the lamp difficult.

What we claim as new and desire to secure by Letters Patent of the United States is:

1. A socket for use with a lamp having spaced contact pins comprising, in combination, a housing of insulating material, spaced contact members carried by said housing, a member rotatably mounted on said housing and being provided with an elongated slot for receiving the lamp contact pins as the latter are moved in alignment

5 into said slot, opposite ends of said slot being formed with lateral recesses extending in opposite directions for receiving the contact pins upon rotation of said member and conducting elements carried by said member projecting into said recesses, said conducting elements cooperating with the said spaced contact members and being adapted to engage the lamp pins for completing an electrical circuit between the lamp pins and said contact members upon rotation of said member.

2. In a socket for use with a lamp having spaced contact pins, a housing of insulating material, spaced contact members carried by said housing, a member rotatably mounted on said housing and being provided with a diametrical slot for receiving the lamp contact pins as the latter are moved in alignment therethrough, the ends of the slot being provided with recesses extending laterally in opposite directions, conducting elements carried by said member and extending into corresponding recesses, said conducting members being in engagement with said spaced contact members, rotation of said member moving the conducting members into engagement with the lamp contact pins and locating the pins in said recesses and guide means carried by said housing and cooperating with the lamp to prevent rotation thereof upon rotation of said member.

3. In a socket for use with a lamp having spaced contact pins, a housing of insulating material having an annular recess therein, an annular member rotatably mounted in said recess, conducting elements carried on diametrically opposite portions of said rotatable member within said recess, spaced fixed contact members carried by said housing and being biased into engagement with corresponding conducting elements, 40 said rotatable member being provided with an elongated slot therein for receiving the lamp contact pins as the latter are moved in alignment therethrough, opposite ends of the slot being provided with recesses extending in opposite directions for receiving the contact pins upon rotation of said rotatable member, portions of the conducting elements extending into the last named recesses for engagement with the lamp pins as the rotatable member is rotated to seat 45 the lamp pins in position in the said last named recesses.
